OF D 765

*Sanford Burnam's
Design of Steel Plate
submitted to Cox Warren Manufacturing Co.
Troy, N.Y.*

Design No 765.

Patented Feb. 12, 1856.

Sanford Burnam, of Troy, N.Y.

Assignor to

Cox, Warren, Morrison, & Co. of Troy aforesaid.

Letters Patent No 765. Dated Feb. 12. 1856.

The schedule referred to in these Letters Patent, and making part of the same.

To all whom it may concern,

Be it known that I, Sanford Burnam of Troy, in the County of Rensselaer, of State of New York, have invented or produced a new & original design of stove plates, which I call the "Triumph", & I do hereby declare that the following is a full, clear & exact description of the same, reference being had to the annexed drawings, making a part of this specification; in which

Fig 1, is a view of the top plate.

Fig 3, a view of the bottom plate.

Fig 5, a view of the end plate.

Fig 7, a view of the side or jamb plate. Figs 2. 4. 6. & 8. are respectively sectional views of the plates, showing curvature of moldings, & plates.

The design of my stove plates is as follows, viz: - A. the top plate is decorated with a wreath of leaves, & branches (a,a). (b,b) are moldings around the edge & on the top.

The design of the bottom plate B, consists of the molding (c,c), & ornaments (d,d), disposed around the hearth plate. The design of the end plate C, consists of the centre ornamental pilaster (e), the panel ornaments (f,f), & Gothic molding (g,g.). The design of the jamb plate D, consists of the ornamental pilasters (h,h,h,) arranged at the ends & center of the plate, the top & bottom moldings (i & j), the panel ornaments (k,k) & the Gothic moldings (l,l), form the rest of the ornamental design of this plate.

Having described my design of Stove
